Des. 229,056
Patented Nov. 6, 1973

229,056

SPRINKLING CAN

Edward C. Grotz, 1505 Harvey Road,
Wilmington, Del. 19810

Filed Aug. 11, 1971, Ser. No. 171,026

Term of patent 14 years

Int. Cl. D23—01

U.S. Cl. D23—11

Fig. 2.

Fig. 1.

*Fig. 3.**Fig. 4.*FIG. 1 is a front view in elevation of a sprinkling can showing my new design;

FIG. 2 is a top plan view thereof;

FIG. 3 is a left side elevational view thereof; and

FIG. 4 is a right side elevational view thereof.

I claim:

The ornamental design for a sprinkling can, substantially as shown.
